DETACHABLE HEEL LIFT

Filed Oct. 31, 1933

UNITED STATES PATENT OFFICE

2,006,995

DETACHABLE HEEL LIFT

Bern Jassen, Brooklyn, N. Y.

Application October 31, 1933, Serial No. 695,987

7 Claims. (Cl. 36—42)

My invention relates to removable or detachable lifts for footwear, together with means for detachably securing a lift to the article of footwear. In my application Serial No. 673,412, filed 5 May 29, 1933, I showed and described a detachable heel lift wherein the lift is shown as pressed against the heel by means of a spiral spring.

The object of the present invention is to provide a detachable lift suitable for use on men's 10 and boys' shoes and oxfords, as well as women's sporting shoes, or other articles of footwear. Since the heels of footwear of this type are comparatively lower in height than the higher heels of women's and girls' dress shoes and the like, 15 there is less capacity in the vertical direction for the employment of a coiled spring of sufficient capacity to hold the lift in place.

I have, in the present case, provided a leaf spring for pressing the lift against the bottom 20 of the heel as distinguished from a spiral or coiled spring, so that the present type of spring, i. e., leaf spring, of sufficient strength and capacity, may be enclosed within a heel of the lower type, that is to say, within the type of heel 25 employed in men's and boys' shoes and oxfords and women's sport shoes. With this type of spring I am enabled to incorporate it in the types of heels referred to and still have sufficient capacity in the movement of the spring 30 for the manipulation of the lift in the manner described herein, and to also have sufficient strength in the spring to hold the larger size lift firmly against the bottom of the heel throughout the extent of the lift.

The lift is detachably applied to a holder or plate which seats within a pocket of the lift, and the lift with the plate referred to is adapted to be held slightly separated from the bottom of the heel against the tension of the spring, while 40 the lift is being attached to or removed from the holding plate. When this plate and the lift are turned to register with the bottom of the heel, the means which previously held the lift separated from the heel is drawn upwardly by 45 the spring concealed within the heel, and the lift is pressed tightly against the bottom of the heel where it is held until such time as it is necessary or desirable to remove the lift to replace it with a new one.

The lift may be made of rubber, leather, or other material although in the drawing I have shown it as made of rubber or rubber composition. When the lift wears out or wears uneven, and it is desirable to replace it, it is only necessary to pull the lift downwardly from the heel 55

and then turn it to lock the lift holding plate separated from the heel. While the parts are in this condition, the worn lift may be removed by sliding it off the holding plate and a new lift may be applied to replace the removed one by simply sliding it over the holding plate and then turning the lift and the plate to register with the heel.

The wearer requires no tools to make the change and the change from one set of lifts to 10 another requires but a few seconds of time to execute. It is intended that the lifts with the plates, hereinafter to be described, shall be sold as articles of manufacture to be applied to any 15 form of footwear to which my invention has been applied.

My invention may and will in many cases be applied to footwear while the same is being made in a factory, but it is also possible to apply my invention to footwear after it has passed from 20 the factory into the hands of the consumer.

Other advantages and improvements will be set forth in the following detailed description of my invention.

In the drawing forming part of this application, 25

Figure 1 is an inverted plan view of a portion of an article of footwear having my invention embodied therein, in which view parts are broken away to show some of the interior construction,

Figure 2 is a sectional view taken on the line 30 2—2 of Figure 1,

Figure 3 is a cross sectional view taken on the line 3—3 of Figure 2,

Figure 4 is a view similar to Figure 1 but showing the lift and the lift carrying plate turned 35 at an angle or to a position suitable for removing or replacing the lift,

Figure 5 is a sectional view taken on the line 5—5 of Figure 4,

Figure 6 is a broken plan view of the lift and 40 the plate attached to it,

Figure 7 is a sectional view taken on the line 7—7 of Figure 6,

Figure 8 is an inverted plan view of the lift carrying plate and the plate which is attached to 45 the heel, these parts being illustrated detached from the heel and lift structures,

Figure 9 is an edge view of the parts shown in Figure 8,

Figure 10 is a bottom or inverted plan view of 50 a heel having a modified form of my invention applied thereto, and

Figure 11 is a sectional view on an enlarged scale and taken on the line 11—11 of Figure 10.

I will first describe the form of my invention 55

shown in Figures 1 to 9 inclusive. I have shown only a portion of an article of footwear, to wit, the heel portion, which is the part to which my present invention relates.

5 I have shown a fragment of the upper 1 above the heel portion of the article of footwear, together with the portion 2 of the article of footwear which forms a heel seat 3 against which the shaped or top side of the heel 4 is adapted to 10 seat. I have also shown the inner lining 5 although this is not related to my invention as it is made the same as in ordinary footwear. The heel 4 is provided with a shaped or curved top surface 6 to conform to and snugly fit against 15 the heel seat 3.

In the form of the invention shown in Figures 1 to 9, the heel may be attached permanently to the heel seat in the same manner as ordinary heels of this type are attached to articles of footwear, which may be by means of tacks and cement, or in any other approved manner, or it may be attached by the prongs of the heel plate as hereinafter described. The heel is shown as provided with a slight depression 7 shaped to conform to 25 the plate 8 which is seated in this recess and is held therein by means of the four lugs 9, 10 projecting upwardly from the plane of the plate 8 and which extend partly or wholly through the heel 4 with their ends clenched for the purpose 30 of securing the plate 8 against the under side of the heel as shown in Figures 2 and 3. The plate 8 has other prongs 11 near its rear end, which are adapted to enter corresponding slots formed in the 35 top side of the heel lift, as will be set forth hereinafter.

The heel, in addition to the recess 7, is provided with a vertical slot or cutout portion 12 for the reception of the leaf spring 13 and also for the reception of the neck 14 of the lift carrying plate 15 at least when the latter is in the 40 position it assumes when the lift is in operative position. The middle portion of the leaf spring is firmly connected with the plate 14 which forms the neck of the lift carrying plate 15, preferably 45 by having a portion of the neck extend through a slot in the middle of the leaf spring and having the end turned over or riveted as shown at 16 to firmly secure the spring to the neck member or a screw 16' may be passed through the spring 50 and be threaded into the neck portion 14, as shown in Figure 3.

This neck member, when in register with the longitudinal slot 12 in the heel plate 8 is adapted to project through this slot and thus allow the lift carrying plate 15 to be pressed upwardly by the 55 leaf spring. The two outer ends of the leaf spring are slightly curved as shown at 17 and these curved ends seat against the upper surface of the heel plate 8. It will be apparent that 60 the tendency of the leaf spring is to press the neck member 14, and therefore the lift carrying plate, upwardly in Figures 2 and 3.

The neck member 14 is so connected with the spring that it may turn or pivot in relation thereto and the spring is prevented from turning with the neck member by indentations 18 formed in the heel plate 8 as shown in Figure 8. These 65 projections lie on opposite sides of each end of the spring as shown in Figure 8, and prevent 70 the spring from turning with the member 14. While this construction is preferable, it is not imperative.

The lift carrying member is shown in Figure 8 as having a curved rear portion 19 with a straight 75 edge 20 adjacent the breast end of the lift. The

lift, as shown in Figures 6 and 7, consists of a body of rubber, leather composition, or other material. In the preferred form the lift consists of a body of rubber or rubber composition suitably moulded and vulcanized. This 5 conforms with the shape of the heel and forms the main body of the lift. There is a plate 21 recessed in the top surface of the lift and preferably this is placed in the mould when the lift is vulcanized, so that portions of the lift material 10 enter apertures 22 in the plate, so that the plate and the body 23 are vulcanized together and remain connected as if they were one body. The lift is formed with a pocket 24 which is 15 preferably curved at the rear end. This pocket 15 extends under the thin wall 25 of the body 23 and under a portion of the plate 21, as shown in Figures 6 and 7.

The plate 21 does not extend to the breast of the lift except for the end extensions 26 but the 20 intermediate portion terminates at the line 27 which is spaced backwardly of the front line 28 of the pocket 24. The plate 21 and the thin wall 25 of the lift have corresponding slots 29 extending from the front end 27 of the plate to a point 25 toward the rear of the plate, the slot being of sufficient width and length to accommodate the neck 14 of the lift carrying plate when the latter registers therewith. The pocket 24 of the lift is 30 adapted to receive therein the lift carrying plate 30 15 which is preferably shaped to conform with the pocket as shown in the drawing.

The forward portion 30 of the pocket 24, in view of the proportions of the parts stated above, remains uncovered by the plate 21 so that there is an 35 opening extending crosswise of the heel lift which is adapted to receive therein either the block 44 attached to the heel as shown in Figure 10, or to receive the upstanding lugs 32 formed on the 40 forward member 33 of the heel plate 8 for the purpose of preventing the lift from turning or shifting when clamped against the bottom of the heel.

As the pocket 24 is not carried to the breast of the heel, there is a wall 34 across the front 45 of the pocket which is the full depth of the lift, and this wall serves to close the front of the pocket to exclude dirt and moisture from the interior parts. Preferably, when the lift is moulded, it is provided around the top edge with a slight 50 projection 35 so that when the lift is held tightly against the heel, the lip 35 will be compressed so that there will be no separation at any point between the outer edge of the lift and the heel.

In the form of the invention shown in Figures 1 55 to 9 inclusive the heel plate 8 will be assembled with the leaf spring as shown in Figures 8 and 9.

The heel will be prepared by forming the pocket 7 to receive the heel plate or the heel may be made with this recess in it. The assembled 60 heel plate may then be attached to the bottom of the heel by means of a press or otherwise by forcing the four lugs 9, 10 through the heel and clenching them on the upper side of the heel; or, if desired, these prongs may be made long enough 65 to extend not only through the heel but through the heel seat, to be clenched on the upper side of the wall 3 of the shoe, so that the prongs not only hold the heel plate in position upon the heel, but also attach the heel to the heel seat. If this 70 arrangement is not desired, the prongs may simply pass through the heel and be clenched at or adjacent the top surface of the heel. This operation firmly and permanently secures the heel plate to the under side of the heel with the prongs 75

11 extending downwardly and with the members 32 also extending downwardly.

The spring has a constant tendency to draw the lift carrying plate 15 upwardly or toward the bottom of the heel. When the neck portion 14 registers with the slot 12 of the heel plate, the spring draws the latter upwardly against the bottom side of the heel plate.

To attach a lift the lift carrying plate 15 is drawn downwardly or away from the heel, against the opposition of the leaf spring; and the plate 15 is turned after the neck 14 has moved out of the slot 12 so that this neck lies at an angle to the slot 12 as shown in Figure 8, or at any other suitable angle. When in this position, the upper end of the neck rests against the bottom surface of the heel plate, whereupon the lift carrying plate is held separated from the heel plate, as shown in Figure 5, ready for the application of the lift to the lift carrying plate.

The lift is then presented with the open portion 38 of the pocket 24 against the curved rear end of the plate 15 whereupon the lift is moved forwardly over the plate 15 with the latter moving down into the pocket 24 under a portion of the lift and under a portion of the plate 21. If the lift is made of compressible material such as rubber, the front wall 34 at the breast of the lift may be more or less compressed or deflected while this operation is taking place.

When the lift has been completely slid onto the plate 15 the forward end of this plate will preferably coincide with the portion 27 of the plate 8, leaving the portion 30 of the pocket in the lift unobstructed. During this operation the neck 14 of the lift plate slides in the slot 29 and remains therein so that the lift plate and the lift will thereafter turn as a unit.

If the form of heel plate shown in Figures 8 and 9 are employed, then when the lift and lift plate are turned so that the neck 14 registers with the slot 12 in the heel plate, the neck will enter this slot, and the lift plate together with the lift will be drawn upwardly by the action of the leaf spring until the top surface of the lift and the top surface of the plate seat snugly against the bottom surface of the heel. When this occurs, the projections 32 on the front end of the heel plate will be received into the portion 30 of the pocket 24 so that the heel lift cannot turn or shift in relation to the heel unless the heel lift and its carrying plate are forced downwardly against the opposition of the spring. In other words, as long as the heel lift remains pressed against the heel, it cannot turn or shift because of the projections 32 of the heel plate. The prongs 11 adjacent the rear of the heel plate also enter small slots at the rear of the lift and also serve to prevent the lift from turning when seated against the heel.

It will be apparent that by employing a leaf spring to force the lift against the heel, I am enabled to employ a spring of ample strength and yet apply the same in a recess of a heel of comparatively low construction. Furthermore, the two ends of the spring having their bearings against the top of the heel plate at considerable distances from the middle portion of the spring, there is considerable leverage which has the effect of amply holding a rather large lift and preventing it from tilting in relation to the heel. This type of spring, therefore, secures a relatively large lift tightly against the bottom of the heel and in the case of large heels it is capable of tightly holding the lift in place.

The wall 34 at the front of the pocket 24 may be used not only in connection with my present invention, but also in the lifts employed in connection with the invention shown in my co-pending application.

If desired, the heel plate may be bolted against the heel and as shown in Figures 10 and 11. In this construction the several prongs 11 shown in the previous construction of the heel plate may be omitted and the shape of the heel plate may be varied as shown in Figure 10, so that it has a rather horseshoe contour around its outer edge. The heel plate is shown at 36 and it will be understood that the lift holding plate 37 will be the same as the one previously described, and it will be attached to the heel plate in the same manner and will be provided with the same kind of spring. The real difference in the construction resides in the method of attaching the heel plate to the heel.

For this purpose I have shown several, to wit, 20 three sleeves 38 having one end each riveted in apertures in the heel plate 36 with the sleeve portions extending upwardly into suitable apertures 39 in the heel.

Not only is the heel provided with these several apertures, but the heel seat 40 is also provided with corresponding apertures which are preferably countersunk to receive the heads 41 of screws which extend through the apertures in the heel seat and screw into the threaded interiors of the sleeves 38. One of these attachments is preferably applied at opposite front corners of the heel plate and another at the back of the heel plate, as shown in Figure 10, although the number and distribution may be varied. It will be observed 35 that these sleeves and screws serve the double purpose of attaching the heel plate 36 in a receiving recess 42 in the heel and also secure the heel to the heel seat. Otherwise, the device operates the same as in the first construction. 40

I have shown a pin or peg 43 in the heel adjacent the back of the heel plate and projecting below the bottom of the heel; and this pin serves the same purpose as the prongs 11 in the first construction. That is to say, it enters the lift when 45 the latter is drawn up against the bottom of the heel and serves to prevent the heel from turning or shifting when it is in operative position.

I have shown a block 44 which may be formed integral with the heel or which may be attached thereto; and this block is received into the front portion 30 of the pocket 24 of the lift when the latter is in operative position and it serves the same as the projections 32 and prevents the heel from turning or shifting when in active position. 55

If desired, the heel proper 4 may be cast or moulded from composition material which may or may not include some percentage of rubber. One advantage of this is that the top shaped surface 6 of the heel, instead of being formed by expensive methods after the heel is made, may be formed in a mould when the heel is being moulded or cast.

In other words, instead of making a heel of leather and then forming the curved surface 6 and cutting out the recess 12, the entire heel 65 may be moulded in one operation with these features formed at the time the heel is moulded, thus reducing the cost of the heel. The heel thus made may be attached to the heel seat in any of the different ways described herein.

From the above it will be apparent that I have provided a device which is very compact and suitable for use in heels of shallow depth; which provides means for quickly detaching and replacing the lift and which will, without screws or 75

other detachable members, firmly hold the lift in place. The device permits the lift to be quickly removed without the use of any tool and without the wearer resorting to the services of the shoe repairer.

5 The use of the leaf spring enables me to secure a firm pressure of the lift against the heel and at the same time arrange the device within a shallow heel. The employment of the wall 34 10 across the front of the portion 30 of the lift pocket protects the interior parts against dust or moisture and it also hides the interior parts so that the finished heel and lift have the same appearance as the ordinary corresponding parts 15 of standard footwear. The different metallic parts of the device may all be made by stamping so that the total cost of the device adds little, if anything, to the cost of the footwear.

20 By making the lifts as shown in Figures 6 and 7 they are sufficiently rigid or resistant to bending to permit the successful use of the lift with the other features of my invention. The reinforcing plate 21 serves both to stiffen the lift against bending and to provide the necessary strength in 25 the top wall above the pocket 24 to hold firmly the lift to the lift carrying plate 15.

While I have shown and described my invention in the preferred forms in great detail, I desire it to be understood that I do not limit my 30 invention to the particular forms herein shown and described except as to those claims which are specifically limited to such details.

Having described my invention, what I claim is:

1. In an article of footwear a heel, a heel plate 35 attached thereto and having a slot, a lift plate adapted to receive and hold a lift against the bottom of the heel, a neck portion on said lift plate adapted to enter the slot of the heel plate when registered therewith and adapted when drawn outwardly and turned at an angle to said slot, to hold the lift plate in position to receive a heel lift thereover, and a leaf spring engaging said heel plate and acting on said neck portion to draw the latter upwardly through the aperture 40 of said heel plate when registered therewith for the purpose of pressing the lift against the heel.

2. An article of footwear having a heel, a heel plate attached thereto and having a slot, a lift plate adapted to receive and hold a lift against the bottom of the heel, a neck portion on said lift plate adapted to enter the slot of the heel plate when registered therewith and adapted to be held against turning while in said slot and adapted when drawn outwardly with said lift plate and turned at an angle to said slot to engage the bottom of the heel plate to hold the lift plate in spaced position from the heel to receive a lift thereover, and a spring engaging said heel plate and pivotally connected with said neck portion 50 and adapted to draw the latter upwardly through the aperture of said heel plate when registered therewith, for the purpose of pressing the lift against the heel.

65 3. In an article of footwear, a heel having a recess, a heel plate attached thereto and extending across said recess and having a slot, a lift plate

adapted to receive and hold a lift against the bottom of the heel, a neck portion on said lift plate, adapted to enter the slot of the heel plate when registered therewith and adapted to be held against turning while in said slot, said lift plate and neck portion adapted to be drawn outwardly away from the heel and to be turned at an angle to said slot whereby the neck portion engages the bottom of said heel plate to hold the lift plate spaced from the heel to receive a lift thereon, and a leaf spring disposed in the recess of said heel, said spring engaging the top of the heel plate and acting on said neck portion to draw the latter upwardly through the aperture of said heel plate when registered therewith, for the purpose of 15 pressing the lift against the heel.

4. A device of the class described including an article of footwear having a heel seat, a heel fitting against said heel seat, a heel plate on the bottom side of said heel, sleeves on said plate extending upwardly into said heel and screws extending through said heel seat and threaded into said sleeves for securing the heel and the heel plate to the heel seat, a lift plate adapted to receive and hold a lift and having a neck portion, 20 said heel plate having an aperture to receive said neck portion therein and a leaf spring acting on said neck portion to move said lift plate toward said heel plate.

5. As an article of manufacture, a heel lift 30 having a pocket extending longitudinally therein and provided with a laterally extending opening at the breast end of said pocket, said pocket adapted to receive a lift plate longitudinally therein, said lift having a slot extending rearwardly from said forward opening in which the neck portion of the lift plate may move, and a stiffening plate imbedded in said lift and extending over a substantial portion of said pocket.

40 6. As an article of manufacture, a heel lift including a major body of moulded material formed with a pocket adjacent the upper side of said body and extending horizontally over the major portion thereof, said lift having a lateral opening at the breast end of said pocket and a 45 metal stiffening plate imbedded and moulded with said body to remain permanently attached thereto, said stiffening plate covering a substantial portion of said pocket and having a slot extending lengthwise of the lift from said open end 50 to form an opening through one wall of said pocket in which the neck portion of a lift plate may move.

7. As a new article of manufacture, a heel lift 55 having a pocket extending longitudinally over a substantial portion of the lift adapted to receive a lift plate horizontally in said pocket, said lift having a top wall extending over the top of said pocket and terminating behind the forward end of said pocket, said lift having a wall at the 60 breast end thereof to form a closure for the forward end of said pocket, said top wall having a slot extending therethrough and running from the front end of said top wall backwardly and in which the neck of a lift plate is adapted to move. 65

BERN JASSEN.
